FIG. 1 is a perspective view of the portion of a tape measure with a claw hook tip of the present invention showing the design in a first, extended position. The dashed lines are shown for environmental purposes only and form no part of the claimed design.

FIG. 2 is a perspective view of the portion of a tape measure with a claw hook tip of the present invention shown in FIG. 1 showing the design in a second, tucked position. The dashed lines are shown for environmental purposes only and form no part of the claimed design.

FIG. 3 is a front view of the portion of a tape measure with a claw hook tip of the present invention shown in FIG. 1. FIG. 4 is a back view of the portion of a tape measure with a claw hook tip of the present invention shown in FIG. 1. FIG. 5 is a top view of the portion of a tape measure with a claw hook tip of the present invention shown in FIG. 1. FIG. 6 is a bottom view of the portion of a tape measure with a claw hook tip of the present invention shown in FIG. 1. FIG. 7 is a side view of the portion of a tape measure with a claw hook tip of the present invention shown in FIG. 1; and,

FIG. 8 is a side view of the portion of a tape measure with a claw hook tip of the present invention shown in FIG. 2. The views in the drawings are shown on different scales. FIGS. 5 through 8 are shown as fragmentary views for ease of illustration.
